UNITED STATES PATENT OFFICE.

DANIEL J. McOSKER, OF PROVIDENCE, RHODE ISLAND.

WRENCH.

No. 844,176.

Specification of Letters Patent.

Patented Feb. 12, 1907

Application filed September 25, 1905. Serial No. 279,886.

To all whom it may concern:

Be it known that I, DANIEL J. McOSKER, citizen of the United States, residing at the city of Providence, in the county of Providence and State of Rhode Island, have invented certain new and useful Improvements in Wrenches, of which the following is a specification, reference being had therein to the accompanying drawings.

10 This invention relates to wrenches, and has for its object to provide a wrench that will automatically bite or tighten its grip upon the work and at the same time automatically lock the jaws against an opening movement when a strain is applied to the operating-handle.

15 A further object of the invention is that the movable jaw may be readily unlocked or released by a slight movement of the operating-handle, thereby allowing said movable jaw a free movement either in or out, after which it may be locked automatically again by another slight movement of said handle.

20 With these and other objects in view the invention consists of certain novel features of construction, as will be more fully described, and particularly pointed out in the appended claims.

25 In the accompanying drawings, Figure 1 is a side elevation of my improved wrench, partly in section, illustrating the manner of engaging and locking the movable jaw by the operating-handle. Fig. 2 is a modification illustrating another means for locking said jaw. Fig. 3 is a transverse sectional view on line 3 3 of Fig. 1, illustrating the wedge shape of the movable jaw and the recess in the body portion of the jaw to receive the same. Fig. 4 is a plan view of the 30 pivoted biting-jaw. Fig. 5 shows the pivoted end of the operating-handle as plain, which is the construction used to engage and bind the shank of the movable jaw when no teeth are employed in either.

35 My improved wrench may be constructed to serve any desired purpose; but the wrenches herewith illustrated are more particularly adapted to be used as a pipe-wrench, but the same general principle may 40 be applied to a monkey-wrench for ordinary use, if desired.

45 Referring to the drawings, at 10 is the body portion of the wrench, through the length of which is formed the hole 11 for the 50 reception of the shank of the movable jaw 16. The side walls of this hole are preferably

drawn together toward the top, forming a tapering hole in transverse section. (See Fig. 3.) The lower forward end 12 of the body portion forms what is hereinafter designated the "fixed jaw," to which jaw is preferably pivoted a hardened toothed face gripping or biting jaw pivoted at 13 through the ears 14. This jaw will swing and adjust itself to better grip or bite the work when the strain is applied to the same, but is designed more particularly to rock and release the grip on the work when the handle is carried back for a new bite.

55 The movable jaw 16 has a shank 17, held to slide longitudinally in the said hole 11 in the body portion. This shank 17 is preferably made tapering toward its upper edge to correspond with and fit into the hole 11 in the body portion, forming a sliding dovetail joint. By constructing this sliding joint in the manner described the wrench is automatically locked against a further opening movement when the strain is applied.

60 On the lower edge of the shank of the movable jaw are preferably formed the teeth 18, which may be cut or cast in any desired shape. Pivoted at 19 in the body of the wrench is the handle 20, on the inner end of which is preferably formed a plurality of 65 teeth arranged to engage those of the shank of the sliding jaw.

65 In my preferred construction, which is that illustrated in Fig. 1 of the drawings, the inner end 21 of the operating-handle 20 is carried into the body portion 10 a short distance beyond the fulcrum-pin 19, and on this end is pivotally mounted on the pin 24 a shoe 22, having teeth 23 formed thereon. When 70 the outer end of the handle is carried downward, the said inner end 21 raises up, causing the teeth of said shoe to engage the toothed portion on the shank, at the same time pressing the said tapered shank upward, which 75 acting automatically binds and holds the shank securely from moving. An essential 80 feature of this construction is that when the pivoted end 21 of the operating-handle is raised it naturally moves on the arc of a circle about its pivot-pin, and by engaging the teeth on the shank the movable jaw is naturally drawn inward slightly, causing it to 85 bite or grip the work automatically when a strain is applied to the operating-handle.

90 The shoe 22 is shown as being a separate piece pivoted to the operating-handle, but this part may be made integral with the said 95

handle, if desired. When it is desired to release this movable jaw, the handle is simply raised and the said jaw is released and free to be moved either in or out. When the tapered shank is used, the movable jaw would be automatically bound and locked on account of its wedging action substantially the same in effect as if there were no teeth employed.

10 In the modification illustrated in Fig. 2 the pivoted end of the handle is formed into the segment of a gear whose center is that of the pivoting-pin 19, a portion of the teeth of this segment being cut away at 22^a, so that when 15 the outer end of the handle 20 is carried into a certain position the said cut-out portion comes opposite the teeth, releasing the same and allowing a free longitudinal movement of the said adjustable jaw. In operating this 20 last-named construction the operating-handle is carried up to release the adjustable jaw, which is then set to the work, after which the handle is brought down, drawing said jaws tightly against the work, causing them to 25 grip with great force. The work may be readily released by carrying the handle back to the required position. The construction is extremely simple and practical and the cost of construction is reduced to the minimum.

Having thus described my invention, what I claim as new, and desire to secure by Letters Patent, is—

1. A wrench comprising a body portion 35 carrying a stationary jaw and provided with an opening having tapered walls, a handle pivoted to said body, a sliding jaw working in said opening and tapered in cross-section, and means carried by said handle for simultaneously imparting an upward and rearward movement to said movable jaw.

2. A wrench comprising a body portion carrying a stationary jaw and provided with an opening having tapered walls, a handle 45 pivoted to said body, a sliding jaw working in said opening and tapered in cross-section, said sliding jaw being provided with teeth, and teeth carried by said handle and meshing

with the teeth of said jaw to cause a simultaneous upward and rearward movement of 50 said movable jaw.

3. A wrench comprising a body portion carrying a stationary jaw and provided with an opening having tapered walls, a sliding jaw working in said opening and tapered in cross-section, a handle having its forward end pivoted to said body, and means carried by the pivoted end of said handle for simultaneously imparting an upward and rearward movement to said movable jaw. 6c

4. A wrench comprising a body portion carrying a stationary jaw and provided with an opening having tapered walls, a handle pivoted to said body, a sliding jaw working in said opening and tapered in cross-section, 65 and a pivoted member carried by said handle for simultaneously imparting an upward and rearward movement to said movable jaw.

5. A wrench comprising a body portion carrying a stationary jaw and provided with an opening having tapered walls, a handle pivoted to said body, a sliding jaw working in said opening and provided with teeth on its lower edge, said sliding jaw having a shank tapered in cross-section, and a pivoted 75 member carried by said handle and provided with teeth for engaging the teeth of said movable jaw to impart a simultaneous upward and rearward movement to the latter.

6. A wrench comprising a body portion 80 provided with a stationary jaw and provided with an opening having tapered walls, a movable jaw provided with a shank working in said opening, said shank being tapered in cross-section, and a handle pivoted to said body portion and provided with means for engaging the under side of the shank of said movable jaw to impart an upward locking movement thereto.

In testimony whereof I affix my signature 90 in presence of two witnesses.

DANIEL J. McOSKER.
